PLIERS FOR ACCURATE ANGULAR BENDING OF METAL STRIPS

Horst Schegulla, Chicago, Ill.

Application December 6, 1954, Serial No. 473,129

4 Claims. (Cl. 81—15)

This invention relates to a plier for accurately bending metal, and is particularly concerned with means for setting the plier to bend metal at a predetermined angle.

The plier constructed in accordance with my invention is provided with means for cutting, punching, and accurately bending metal strips, wires and rods.

Conventional pliers are often used for bending metal strips, wires, and rods, but accuracy in bending to a specific angle has been attained only by the laborious method of trial and error. Of course metal may be bent accurately on a brake, but a brake is not always available. Furthermore, brakes are not portable and cannot be used away from the shop. Another disadvantage of a brake is that it is limited to three consecutive right angles in a single strip of metal because the angle formed by the first bend interferes with positioning the metal in the brake for a fourth bending operation.

My improved plier may be carried like an ordinary plier and will accurately bend a metal strip as many times as desired, since no bend interferes with positioning the metal for a subsequent bend as long as the bends are spaced apart a distance at least as great as the depth of the bending die.

The plier is provided with means for setting the angle at which the metal is to be bent and with means to prevent the metal from slipping so that the bend is not only accurate, but is also at the intended place in the metal. The jaws for bending the metal may be pivoted to each other as in conventional pliers, or may be arranged to move parallel to each other.

The structure by which the above mentioned and other advantages of the invention are attained will be described in the following specification, taken in conjunction with the accompanying drawings, showing several preferred illustrative embodiments of the invention, in which:

Figure 1 is a side elevational view of one form of plier embodying the invention;

Fig. 2 is a cross sectional view, taken along the line 2—2 of Fig. 1, and showing the gage means for setting the plier for any specific angle of bend;

Fig. 3 is a cross sectional view, taken along the line 3—3 of Fig. 2, and showing the internesting engagement of the cooperating gage members;

Fig. 4 is a cross sectional view, taken along the line 4—4 of Fig. 1, and showing the relationship between the male and female dies;

Fig. 5 is a side elevational view of a modified form of plier in which the bending jaws move parallel to each other;

Fig. 6 is a cross sectional view, taken along the line 6—6 of Fig. 5;

Fig. 7 is a cross sectional view, taken along the line 7—7 of Fig. 5, and showing the stop means for limiting the inward movement of the jaws;

Fig. 8 is a view, similar to Fig. 5 showing a strip of metal being bent between the jaws;

Fig. 9 is a cross sectional view, taken along the line

2

9—9 of Fig. 8, and showing the relationship between the metal and the bending dies just before the start of the bending operation;

Fig. 10 is a fragmentary cross sectional view showing the means on the male die for engaging the metal to be bent;

Fig. 11 is a side elevational view showing different gage means; and

Fig. 12 is a view, similar to Fig. 11 showing micrometric gage means which also serve as stop means for limiting the inward movement of the jaws.

Referring to Fig. 1 of the drawings, the plier comprises a pair of complementary plier members 2 and 3 pivoted together adjacent their upper ends by a screw 4. The member 2 includes a female die 5 of substantially rectangular horizontal cross section and a curved handle 6 integral therewith. The member 3 includes a male die 7 of substantially rectangular horizontal cross section and a curved handle 8 integral therewith. Dies 5 and 7 are of the same length, and handles 6 and 8 are symmetrical, both being curved outwardly at their center to form convenient gripping surfaces. On the opposite side of pivot screw 4 members 2 and 3 are provided respectively with cutting jaws 9 and 10 having sharp meeting edges 20 so that they may cooperate to cut a strip of metal inserted therebetween.

Members 2 and 3 also have extensions 11 and 12, respectively, which cooperate to form a punch for metal inserted in a notch 13 in extension 11. Both extensions 30 11 and 12 are provided with axially aligned bores 14 and 15. Bore 14 extends completely through extension 11 at right angles to notch 13 by which it is intersected. Extension 12 is provided with a notch 16 and bore 15 extends from notch 16 to the edge of extension 12 adjacent extension 11. A punch pin 17 has an enlarged head positioned in notch 16 and a shank extending through bore 15 and into bore 14. When handles 6 and 8 are moved outwardly a short distance punch pin 17 clears recess 13 to permit entry of the metal strip to be punched. 40 Inward pressure on the handles then moves extensions 11 and 12 together to force punch pin 17 through the metal strip held in recess 13.

Extension 12 is provided with a flat arcuately shaped depression spaced a short distance from screw 4, as indicated at 18, and the upper end of die 5 is provided with a similar depression 19. Extension 11 and the upper end of die 7 are provided with complementary depressions (not shown) on their opposite surface to permit pivotal movement of cutting jaws 9 and 10 and extensions 50 11 and 12 within the planes defining the thickness of the plier. Each depression has a depth of approximately half the thickness of the plier so that the normal thickness of the plier is not increased in the area adjacent the pivot where the parts overlap. A stop member 12' is secured to extension 12 and is adapted to engage the upper end portion of die 7 when handles 6 and 8 are spread outwardly, to limit the outward movement of plier members 2 and 3.

The upper and lower inside edge portions of die 5 60 are aligned parallel to the outer edge portion, as indicated at 20 and 21, respectively. The upper and lower inside edge portions of die 7 are similarly aligned, as indicated at 22 and 23. A set screw 24 extending through a transverse bore 25 in die 5 abuts surface 23 65 of die 7 to limit the inward movement of plier members 2 and 3. Set screw 24 is preferably provided with a lock nut 24' to prevent accidental displacement of the screw after it has been set for any particular bending operation.

70 The intermediate portion of the edge of die 5 facing the corresponding portion of die 7 is offset towards die 7, as indicated at 26, and is provided with a longitudinally

extending V-shaped groove 27. Lips 28 and 29 extend from opposite ends of the intermediate portion of die 5 to facilitate positioning of the metal strip for bending. The distance between lips 28 and 29 determines the width of the strip of metal that may be bent by the plier.

The intermediate portion of the edge of die 7 facing die 5 is tapered to provide a sharp edge 30. Edge 30 is provided with a laterally projecting tit 31. When a strip 32 of metal is inserted between lips 28 and 29 and handles 6 and 8 are pressed together, tit 31 engages the metal to start the bending. The tit bites into the metal, as shown in Fig. 10, and prevents it from slipping thereby insuring that the bend will be properly positioned. Tit 31 projects only very slightly beyond the rest of edge 30, so that as the bending progresses and the angle of the metal strip 32 becomes sharper, the penetration of the tit into the metal strip will become less noticeable. When the bending is complete and the metal strip is removed from between dies 5 and 7 the impression of the tit on the metal will not be noticeable.

The final angle of the metal strip will be determined by the relative inward movement of edge 30 towards groove 27. This inward movement is controlled by the setting of set screw 24. In order to regulate the setting of set screw 24 to insure accuracy in the angularity of the bend, I have provided gage means comprising a pair of complementary gage members 33 and 34 secured to handles 6 and 8, respectively, by rivets 35 and 36. Gage member 33 is bifurcated to provide spaced parallel arms 37 and 38, and gage member 34 is provided with an arm 39 fitting snugly therebetween. Arm 39 is provided with a scale 40 calibrated to indicate various angles. Arms 37 and 38 are recessed on their top edge, as indicated at 41, to facilitate reading scale 40.

The operation of the plier is very simple. In order to bend a strip of metal to a specific angle, handles 6 and 8 are moved to position the outer end 42 of arm 37 or 38 in registration with the mark of scale 40 which indicates the desired angle. Set screw 24 is then threaded into bore 25 until its end abuts edge 23 of die 7, and lock nut 24' is then tightened to hold the set screw in place. Handles 6 and 8 are then moved outwardly to permit positioning of the metal strip between groove 27 of die 5 and edge 30 of die 7. Inwardly applied manual pressure on handles 6 and 8 will bend the metal strip. When the desired angle is reached, edge 23 abuts the end of set screw 24 and prevents further inward movement of the handles.

The embodiment of Figs. 5 to 8 is substantially similar to that previously described, the only difference being that the bending dies 5' and 7' are arranged to move in parallel planes instead of pivotally. Duplicate parts will be indicated by the same reference numerals, and the description will not be repeated.

Handle 6' is bifurcated to form separated side walls 43 and 44, as shown in Fig. 7, and handle 8' is bifurcated to form side walls 45 and 46. Side walls 43 and 45 are pivoted together by a rivet 47, and side walls 44 and 46 are similarly pivoted together by a rivet 48. Each of the side walls extends beyond the pivot point to provide ears 49 and 50. Female die 5' is secured between ears 50 by a rivet 51 which permits relative pivotal movement between the die and ears 50. Male die 7' is similarly secured between ears 49 by a rivet 52.

A slot 53 extends longitudinally from the lower end of die 5', and a similar slot 54 is provided in die 7'. A rivet 55 extending transversely between side walls 43 and 44 is positioned in slot 53, and a rivet 56 extending between side walls 45 and 46 is positioned in slot 54 to maintain the dies 5' and 7' in parallel relationship as they are moved relative to each other by the pivotal movement of handles 6' and 8'.

The embodiment of Fig. 11 is a duplicate of Fig. 1 except that different gage means is provided for positioning set screw 24 to provide a desired angle in bending the

metal strip. In this embodiment gage members 33 and 34 are eliminated, and a scale 57, calibrated in angles, is marked on extension 12'. A line 58 is marked on extension 11'. Handles 6 and 8 are moved until line 58 coincides with the portion of scale 57 indicating the particular angle desired. Set screw 24 is then set as hereinabove described.

In the embodiment of Fig. 12 a different gage is disclosed and the cutting jaws and the punch have been omitted. Set screw 24 has also been omitted since the gage combines the functions of the set screw and the gages of the other embodiments. A stud 59 is secured to handle 8" by a rivet 60. A scale 61, calibrated in angles, is inscribed on the circumference of stud 59. Stud 59 is provided with a threaded shank 62 and a tubular sleeve 63 is threaded on the shank. Sleeve 63 is rotated relative to stud 59 until its inner end indicates the desired angle. The outer end of sleeve 63 is flat, as indicated at 64, and a flat recess 65 is provided on the inside of handle 6" to insure accuracy in limiting the movement of handles 6" and 8" in accordance with the setting of sleeve 63. The threaded engagement of sleeve 63 and shank 62 permits the plier of this embodiment to be set with micromatic accuracy.

It will be obvious that the gage shown in Fig. 12 may be provided on the embodiments of Figs. 5 to 8, and the cutting and punching means of Fig. 1 may be provided on the embodiment of Fig. 12.

While I have described a few preferred embodiments of my invention in detail, it will be understood that the description thereof is illustrative rather than restrictive, as many details may be modified or changed without departing from the spirit or scope of my invention. Accordingly, I do not desire to be restricted to the exact structure described.

I claim:

1. A plier for accurately bending metal to a predetermined angle comprising a pair of jaw members, a pair of handles movable pivotally to move said jaw members in parallel relationship towards and away from each other, said jaw members having meeting edges provided with cooperating male and female dies, a tit projecting laterally from said male die to engage a strip of metal positioned between said dies, upon inward movement of said jaws, to initiate bending of said metal strip before the strip is engaged by the major bending surface of said male die, and a screw extending through one said jaw members and adapted to engage said other jaw member to prevent inward pivotal movement of said handles beyond any predetermined point.

2. A plier for accurately bending metal to a predetermined angle comprising a pair of jaw members, a pair of handles movable pivotally to move said jaw members towards and away from each other, said jaw members having meeting edges provided with cooperating male and female dies, said female die having laterally projecting lips at the opposite ends thereof to facilitate positioning of a metal strip between said dies for bending, a tit projecting laterally from said male die to engage a strip of metal positioned between said dies upon inward movement of said handles, said tit initiating the bending of said strip of metal before the strip is engaged by the major bending surface of said male die, gage means to indicate the angle of bend for any pivotal position of said handles, and means for preventing inward pivotal movement of said handles beyond any predetermined point.

3. A plier for accurately bending metal to a predetermined angle comprising a pair of jaw members, a pair of handles movable pivotally to move said jaw members towards and away from each other, said jaw members having meeting edges provided with cooperating male and female dies, a tit projecting laterally from said male die to engage a strip of metal positioned between said dies upon inward movement of said handles, said tit initiating the bending of said strip of metal before the

strip is engaged by the major bending surface of said male die, gage means to indicate the angle of bend for any pivotal position of said handles, one of said jaw members being provided with a threaded bore extending transversely therethrough, and a set screw threaded into said bore, said set screw being adjustable to engage said other jaw member at any predetermined point upon inward movement of said handles to control the angle of bend of a metal strip positioned between said dies.

4. A plier for accurately bending strip material to a predetermined angle comprising a pair of handles pivotally connected adjacent one end thereof, each of said handles having an extension beyond the pivotal connection, a pair of jaw members each pivotally secured to one of said extensions, means engaging each of said jaws to maintain them in parallel relationship, a screw adjustably secured in one of said jaws, said screw being engageable with said other jaw to limit the movement of said jaws towards each other, said jaws having cooperating male and female dies to engage opposite surfaces of a

strip of metal positioned between them, said dies being operable, upon inward movement of said jaws, to bend a strip of metal positioned between them, and a tip projecting from said male die to engage a strip of metal to hold it firmly against said female die at the start of said bending operation.
